UNITED STATES PATENT OFFICE

141,377

DESIGN FOR A VANITY OR SIMILAR ARTICLE

Edwill B. Miller, Red Lion, Pa., assignor to Red Lion Table Company, Inc., Red Lion, Pa., a corporation of Pennsylvania

Application March 22, 1945, Serial No. 118,638

Term of patent 7 years

(Cl. D33—6)

To all whom it may concern:

Be it known that I, Edwill B. Miller, a citizen of the United States, residing at Red Lion, in the county of York and State of Pennsylvania, have invented a new, original, and ornamental Design for a Vanity or Similar Article, of which the following is a specification, reference being had to the accompanying drawing forming part thereof.

Figure 1 is a view in perspective of a vanity or similar article showing my new design.

Figure 2 is a view on an enlarged scale of a portion of one end of the face of a drawer.

ure 2.

I claim:

The ornamental design for a vanity or similar article, substantially as shown.

EDWILL B. MILLER.
